US0D1087782S

(12) **United States Design Patent** (10) Patent No.: **US D1,087,782 S**
(45) Date of Patent: ** Aug. 12, 2025

(54) **DEODORIZER CASE**

(71) Applicant: **Shaoxing Dingrun Technology Co., Ltd.**, Shaoxing (CN)

(72) Inventor: **Wuying Du**, Shaoxing (CN)

(73) Assignee: **Shaoxing Dingrun Technology Co., Ltd.**, Shaoxing (CN)

(**) Term: **15 Years**

(21) Appl. No.: **29/952,878**

(22) Filed: **Jul. 18, 2024**

(51) LOC (15) Cl. **23-04**

(52) U.S. Cl.

USPC **D23/367**; D23/368
